[57] CLAIM

The ornamental design for an aircraft, as shown and
described.

DESCRIPTION

FIG. 1 is a front perspective view of an aircraft showing
my new design;

FIG. 2 is a side elevational view thereof with the wheels
extended condition, the opposite side elevational view
being a mirror image of that shown.

FIG. 3 is a top plan view thereof;

FIG. 4 is a front elevational view thereof.
